US00D862687S

(12) **United States Design Patent** (10) Patent No.: **US D862,687 S**
(45) Date of Patent: **** Oct. 8, 2019**

(54) **SURGICAL MASK**(71) Applicant: **Revolutionary Medical Devices, Inc.**,
Mettawa, IL (US)(72) Inventors: **Thomas M. Reilly**, Tucson, AZ (US);
Michael J. Pedro, Brooklyn, NY (US);
Steven H. Cataldo, New York, NY
(US); **Ryan G. Redford**, Tucson, AZ
(US); **David M. Kane**, Tucson, AZ
(US)(73) Assignee: **Revolutionary Medical Devices, Inc.**,
Mettawa, IL (US)(**) Term: **15 Years**(21) Appl. No.: **29/657,380**(22) Filed: **Jul. 20, 2018****Related U.S. Application Data**(63) Continuation of application No. 29/530,124, filed on
Jun. 12, 2015, now Pat. No. Des. 825,740, which is a
continuation-in-part of application No. 29/520,420,
filed on Mar. 13, 2015, now abandoned, which is a
continuation-in-part of application No. 29/511,716,
filed on Dec. 12, 2014, now abandoned.(51) LOC (12) Cl. **29-02**

(52) U.S. Cl.

Primary Examiner — Lilyana Bekic(74) *Attorney, Agent, or Firm* — Morgan, Lewis &
Bockius LLP**CLAIM**The ornamental design for a surgical mask, as shown and
described.**DESCRIPTION**FIG. 1 is a front elevational view of a surgical mask showing
our new design;

FIG. 2 is a right side view thereof;

FIG. 3 is a left side view thereof;

FIG. 4 is an exploded bottom perspective view thereof;

FIG. 5 is bottom perspective view thereof; and,

FIG. 6 is front perspective view thereof, with the lower
portion removed.The broken lines in the Figures illustrate portions of the
surgical mask that form no part of the claimed design.**1 Claim, 6 Drawing Sheets**| (56)	References Cited
